UNITED STATES PATENT OFFICE.

CLINTON E. LARRABEE, OF BINGHAMTON, NEW YORK, ASSIGNOR TO INTERNATIONAL TIME RECORDING COMPANY OF NEW YORK, OF ENDICOTT, NEW YORK, A CORPORATION OF NEW YORK.

MULTICOLORED RIBBON-CONTROL DEVICE FOR TIME RECORDERS.

Application filed January 20, 1925. Serial No. 3,574.

The present invention relates to improvements in time recorders and is more particularly directed to improvements in the two color ribbon mechanism of such recorders.

- 5 The invention has among its objects the provision of a ribbon shifting mechanism which is simple, durable, inexpensive to manufacture and which will not readily get out of order when in use.
- 10 Other objects of the invention will appear as the invention is hereafter disclosed in the appended specification and claims and shown in the drawings which by way of illustration show a preferred embodiment of the invention.
- 15

In the drawings:

Fig. 1 shows a front view of a recorder equipped with my improvement.

Fig. 2 is a side elevation of the same.

- 20 Fig. 3 is a plan view of the parts shown in Fig. 4.

Fig. 4 is a detail view of the ribbon shifting controlling elements of the machine.

- 25 Referring to the drawings, 10 designates diagrammatically the group of time type wheels which are driven by the clock train in the usual manner. Also driven by the clock train, is a program disk 11 (Fig. 1) carrying the usual adjustable camming projections 12.
- 30 The program disk is utilized to control two color ribbon mechanism in the following manner. Suitably pivoted at the top of the machine and cooperating with the camming lugs 12 is a pivoted lever 13 having connected thereto a depending link 14, which link at its lower end connects to a lever 15 pivoted at 16 (see Fig. 2). A pawl 18 is pivoted on the end of lever 15 and is normally urged in a clockwise direction by a spring 17. The 35 nose of the pawl 18 is bent over, as shown at 19, and this portion is adapted to engage with a serrated disk 20. Upon the upward movement of link 14 the pawl end 19 passes out of a notch in disk 20 with which it had been in engagement and first rides over the right side of pin 21 carried on a locking pawl 22 which is pivoted at 23. After passing above pin 21 the end 19 snaps across the top of the pin into contact with the serrated disk. Immediately afterwards link 14 drops suddenly and the pawl tip 19 cams locking pawl 22 out of engagement with the serrated disk and thereafter the pawl drops into the next notch

and advances the serrated disk 20 one notch. It will be understood that one step of movement is imparted to the serrated disk 20 each time a color change is to be effected upon the ribbon. Fixed to disk 20 to rotate in unison therewith is a serrated cam or star wheel 24. Cooperating with this cam there are follower pins 25 fast to a bell crank lever 26 pivoted at 27 and having an upwardly extending end 28 extending to and cooperating with the color flag visual indicator 29. Arm 28 also carries a pin 30 which fits in a T-shaped element 31. This T-shaped element is provided with two shoulders 32 and 33 and is adapted to be lifted upwardly at each operation of the printing manual 34 by means of the linkage 35, 36, 37 and 38. The two color ribbon 70 40 is carried on the usual spools 41 and 42. Each spool is fixedly secured to shafts 43, each of which shafts at its lower end is provided with a flanged sleeve 44 adapted to receive lever arms 45. These lever arms 45, as shown in Fig. 2, are fixed to a shaft 46, which shaft also has fixed thereto a pair of arms 47 connecting with vertical rods 48 which extend to and support a frame 49 which serves as a guide for the ribbon adjacent the impression point. It will be understood that if shaft 46 is rocked clockwise the lower portion of the ribbon will be aligned with the printing wheels and if the shaft 46 remains in the position shown in Fig. 2 the upper portion of the ribbon will effect the imprint. The arrangement described provides means for not only elevating the ribbon spools but also elevating or lowering the ribbon guide. In order to effect the rocking movement of shaft 90 46 an arm 50 is provided which is fast to shaft 46 and has connected thereto a link 51 extending upward and connects with one end of a walking beam 52. The walking beam is pivoted at 53 and is provided with two pins 95 54, 55.

Whenever the printing handle 34 is depressed during the first part of its travel the downwardly projecting arm 35 moves link 36 to the right and this link in turn rocks member 37 and part 38 anticlockwise. This movement elevates the slotted member 31. Although this member 31 moves in a substantially vertical path that path varies in detail according to the position of pin 30, which position is in turn determined by the position

of bell crank 28. In the position in Fig. 2 shoulder 32 on member 31 will on every up stroke engage the pin 54 on walking beam 52 thereby rocking the walking beam clockwise 5 and drawing up on link 51 thus elevating the ribbon as previously described.

The ribbon may or may not remain in upper position after a recording operation. If it remains in upper position and if member 31 is shifted to the right prior to the next recording operation the member 31 upon the next rising stroke will have its shoulder 33 engage pin 55 thus rocking walking beam 52 anticlockwise and causing a lowering of 15 the ribbon. It will be understood that if member 31 is shifted to left hand position shoulder 33 will clear pin 55 upon the rising of member 31. Also if member 31 is in the right hand position pin 54 will clear shoulder 20 32.

Fig. 4 shows the parts in the position which they assume after a recording operation on the lower section of the ribbon but before part 31 has been raised upon a subsequent 25 printing operation to reshift the ribbon back to lower position. It will be understood that the subsequent operation of the printing manual with the parts in the position shown in Fig. 4 will cause a printing on the upper 30 section of the ribbon.

The arrangement described provides means for setting or controlling the position of the combined actuating and controlling member 31 in such a way that after it is set it is locked 35 in position and only released at a time of a new setting. All ribbon shifting movements are positive in their nature and the use of gravity or springs for this purpose is obviated. Furthermore, if the ribbon is to 40 remain in one position, this may occur without the necessity of the member 31 being again required to rock the walking beam or element 52 and reshift the ribbon shifting mechanism.

45 What I claim is:—

1. In a time recorder, in combination with a controlling member for controlling ribbon shifting operations, means for controlling the position of said member, said means including a time driven program wheel, a notched disk intermittently advanced under control of said program wheel, a star wheel rotatable with said notched disk, a follower cooperating with said star wheel and connections 50 therewith for controlling the position of the controlling member, and means for positively locking said notched disk and said cooperat-

ing star wheel against advance, or retraction after each advance thereof.

2. In combination with a controlling member for predetermining ribbon shifting operations in a time recorder having a multicolor ribbon mechanism, means for setting said member, comprising a time driven program wheel, an assembly comprising a notched wheel and a cam wheel mounted to rotate in unison, a pawl controlled by the program wheel for engaging said notched wheel and advancing the said assembly step by step, a locking pawl coacting with said notched wheel for positively locking said assembly against advance or retraction after each advance thereof, and a follower device cooperating with said cam wheel and connected to the controlling member for setting the same. 75

3. The invention set forth in claim 2 in which means is provided for unlocking the locking pawl prior to each step of advance of the assembly.

4. In a time recorder, in combination with a controlling member for controlling ribbon shifting operations, means for controlling the position of said member, said means including a time driven program wheel, a disc having rectangular slots in its periphery and intermittently advanced under control of said program wheel, a star wheel rotatable with said disc, a follower cooperating with said star wheel and connections therewith for controlling the position of the controlling member and a latching pawl mounted on a fixed pivot and cooperating with the rectangular slots in the disc for positively locking said disc and said star wheel against movement in either direction in the absence of an advancing operation under control of the program wheel. 90

5. In a time recorder, in combination with a controlling member for controlling ribbon shifting operations, a time-driven program wheel, a disc with straight-sided notches in its periphery, a driving pawl controlled by the program wheel for engaging said notches to drive the disc, a locking pawl for engaging said notches to lock the disc against rotation in either direction, means whereby retraction of said driving pawl from said notches forces said locking pawl into firm engagement with said notches, and means actuated by said disc for controlling said ribbon controlling member. 105

In testimony whereof I hereto affix my signature.

CLINTON E. LARRABEE.
